UNCOUPLING MECHANISM.

1,226,094.

Specification of Letters Patent.

Patented May 15, 1917.

Application filed February 2, 1917. Serial No. 146,132.

To all whom it may concern:

Be it known that we, WILLIAM McCONWAY, Jr., and WILLIAM J. REGAN, citizens of the United States, residing at Pittsburgh, 5 in the county of Allegheny and State of Pennsylvania, have invented certain new and useful Improvements in Uncoupling Mechanism; and we do hereby declare the following to be a full, clear, and exact description of the invention, such as will enable others skilled in the art to which it appertains to make and use the same.

Our invention relates to uncoupling mechanism by which the trainman may actuate 15 the locking device of a car coupler from a point at one side of the car. The principal object of the invention is to provide simple, strong, effective and easily assembled uncoupling mechanism which is especially 20 suited for coöperation with a coupler that is provided with knuckle locking devices designed to be actuated from above the coupler head. Generally stated, this and other objects of the invention of less importance are 25 attained, as will hereinafter appear, by combining with the coupler locking mechanism a transversely extending rotatable uncoupling lever which is supported at its inner end by a member that is journaled on a 30 bracket rigidly secured to the car framing at one side of the car coupler, and by interposing between such coupler locking mechanism and the pivoted member by which the uncoupling rod is supported a curved arm 35 or lock engaging member which is pivotally connected to said supporting member and has slideable engagement with the locking mechanism.

In the drawings, which illustrate the preferred form in which we contemplate applying our invention,

Figure 1 is a plan view of an uncoupling mechanism embodying the invention, illustrating its relation to the car coupler and 45 the body of the car.

Fig. 2 is a front elevation of the features of construction illustrated in Fig. 1.

Fig. 3 is a detail side elevation of the construction illustrated in Figs. 1 and 2.

50 Fig. 4 is a detail sectional view of the mechanism, taken on the line 4—4, Fig. 1.

Fig. 5 is a detail view of a portion of the mechanism partly in elevation and partly in vertical section on the line 5—5, Fig. 4.

Fig. 6 is a detail plan view of one of the 55 elements of the mechanism, and

Fig. 7 is a side elevation of the bracket device by which the outer end of the uncoupling rod is supported.

In the drawings, 1 indicates a portion of 60 the end sill of a car, and 2 is a car coupler. The coupler is provided with locking mechanism 3 performing the usual function of normally preventing the knuckle 4 from rotating to open position. As shown, the 65 lifter 3 of such locking mechanism preferably extends through the upper wall of the coupler head, and is provided with an eye or opening 5 that receives and permits sliding movement of a curved arm or operating 70 arm 6 that is actuated by a rotatable uncoupling lever 7 whose operating handle 8 normally hangs vertically adjacent to the side of the car within convenient reach of 75 the trainman.

The member 6 which engages the knuckle locking mechanism of the coupler is preferably curved circularly, as at 9, and is provided at its inner end with a perforated sleeve 10 which is journaled in a socket or 80 recess 11 formed in the member 12 by which the inner end of the uncoupling rod 7 is supported.

The upper and lower walls of the member 12 are provided with aligned pivot openings 85 13 through which and through the opening in the sleeve 10 the upturned inner end 14 of the uncoupling lever 7 is adapted to pass. The curved lock engaging member 6 is thereby pivotally secured to the member 12 with 90 in the socket 11 thereof. The member 12 is rotatably mounted upon the car body. To this end it is preferably provided with oppositely disposed horizontally extending 95 pintles 15 which are journaled in corresponding bearings 16 formed on a bracket 17 which may be rigidly secured to the end sill 1 by means of bolts 18. As shown in Figs. 1 and 3, the bearings 16 are open at the top and the pintles 15, therefore, merely 100 rest in such bearings. To prevent the member 12 from becoming disassociated from its bearing bracket 17, portions 19 of the inner faces of the upright arms of the bracket are curved concentric with the bearings for the 105 pintles 15, and the member 12 is provided on opposite sides with lugs 20 which, when the parts are in assembled relation, extend

beneath and in close proximity to the corresponding curved shoulders 19, thus preventing the socketed member 12 from moving upwardly so as to permit the pintles 15 to escape from their bearings. At its lower end the member 12 is preferably provided with a shelf or bar 21 which forms a seat or support for the inner end of the rotatable uncoupling lever 7. The outer end of the uncoupling lever is preferably supported by means of a rearwardly opening bracket 22 which is secured to the end sill 1 by bolts 23, a cotter 24 being preferably employed to prevent the uncoupling lever 7 escaping from the bracket.

To assemble the mechanism the member 12 is brought to an approximately horizontal position so as to permit pintles 15 thereof to be positioned in their bearings 16. The member 12 is then rotated until its lugs 20 stand beneath the curved shoulders 19 of the bracket 17. The curved arm 9 of the member 6 is then passed through the opening 5 in the lifter 3 of the coupler locking mechanism and the inner end or sleeve 10 of the member 6 is positioned in the socket 11 of the member 12. The uncoupling lever 7, while being held longitudinally of the car, is lifted until its upturned inner end 14 enters the corresponding alined pivot openings in the members 6 and 12. The uncoupling lever is then rotated horizontally about its upturned portion 14 as a pivot until its outer end is brought into assembled relation with the stationary supporting bracket 22, when its inner end rests upon the supporting shelf 21 carried by the member 12. When the opening in the bracket 22 has been closed by the cotter 24 so as to prevent the escape of the uncoupling lever 7 therefrom, the parts of the uncoupling mechanism are so interlocked that they cannot become accidentally disconnected; but it will be noted that it is only necessary to remove the single cotter 24 in order to permit the entire mechanism to be disassembled.

When the trainman grasps the handle 8 of the uncoupling lever and moves it forwardly and upwardly in the usual manner the member 12 rotates on its pintles in the bearing bracket 17, as will be readily understood, thus causing a corresponding rotation of the operating member 6 which is connected to the lifter 3 of the knuckle locking mechanism. This causes the locking mecha-

nism to perform an unlocking operation. When the coupler 2 moves laterally, as is the case when the car passes around a curve, the curved portion 9 of the member 6 slides through the opening 5 in the top of the lock lifter 3; and when the coupler moves longitudinally of the car in draft and buffing the member 6 swings or pivots upon the upturned end 14 of the uncoupling lever and also slides through the opening in the upper end of the lifter 3 as already described.

We claim:

1. In an uncoupling mechanism for car couplers, the combination with the coupler locking mechanism, of a rotatable uncoupling lever, a bracket secured to the car at one side of the coupler, a member journaled on said bracket and a lock actuating member operatively connected to and having slidable engagement with said locking mechanism, said uncoupling lever constituting means for pivotally connecting said lock actuating member to the member journaled on said bracket.

2. In an uncoupling mechanism for car couplers, the combination with coupler locking mechanism, of a rotatable uncoupling lever, a bracket rigidly secured to the car at one side of the coupler, a supporting member for said uncoupling lever pivotally mounted on said bracket, and a curved member pivotally connected to said supporting member and operatively connected to and having slidable engagement with said coupler locking mechanism.

3. In an uncoupling mechanism for car couplers, the combination with coupler locking mechanism, of a rotatable uncoupling lever journaled on the car and extending toward the side thereof, a bracket secured to the car and having a plurality of bearing members, a socketed member having pintles adapted to be journaled in said bearing member, and a curved member operatively connected to and having slidable engagement with said locking mechanism, said curved member extending into said socket and being pivotally connected to said socketed member by means of said uncoupling lever.

In testimony whereof we affix our signatures.

WILLIAM McCONWAY, JR.
WILLIAM J. REGAN.
